Primary Examiner — Patricia A Palasik

(57) **CLAIM**

The ornamental design for a linear actuator, as shown and described.

DESCRIPTION

1. Linear actuator
- 1.1 : Perspective
- 1.2 : Front
- 1.3 : Back
- 1.4 : Right
- 1.5 : Left
- 1.6 : Top
- 1.7 : Bottom

1 Claim, 7 Drawing Sheets(56)
